UNITED STATES PATENT OFFICE.

SEVERIN HALVORSON, OF CHICAGO, ILLINOIS, ASSIGNOR TO BARNHART BROTHERS & SPINDLER, OF CHICAGO, ILLINOIS, A CORPORATION OF ILLINOIS.

GRIPPING DEVICE FOR PRINTING-PRESSES.

SPECIFICATION forming part of Letters Patent No. 744,538, dated November 17, 1903.

Application filed December 29, 1902. Serial No. 137,052. (No model.)

To all whom it may concern:

Be it known that I, SEVERIN HALVORSON, a citizen of the United States, residing at Chicago, in the county of Cook and State of Illinois, have invented a certain new and useful Improvement in Gripping Devices for Printing-PresSES, of which the following is a full, clear, concise, and exact description, reference being had to the accompanying drawings, forming a part of this specification.

My invention relates to gripping devices for printing-presSES by which the paper is gripped to the rotary printing-press cylinder or to other similar element of the press.

It has been found that in the operation of printing-presSES the various gripping-fingers now in use which are employed to grip the paper and hold it down upon the bed for the printing operation are defective and do not give entire satisfaction. This is because they rebound slightly from the cylinder after being swung or moved down upon the same to grip the paper, and the rebound permits the paper to shift a little upon the cylinder. The

result is that the printing is not satisfactorily done. The impression is not in the right place, which is especially objectionable in color-work where the same paper is run through the press several times.

The object of the invention is to provide a gripping device which will overcome these objections and which when swung or moved down to grip the paper will not rebound, but will maintain from the very beginning its original hold upon the paper.

In the accompanying drawings, Figure 1 is a plan view of a portion of a printing-press having a plurality of gripping devices embodying my invention. Fig. 2 is a section

taken on line 2-2 in Fig. 1. Fig. 3 is a side view of the gripping device, and Fig. 4 is an edge view of the same.

In Figs. 1 and 2 I have shown a feed-table 1, which is understood to be suitably incorporated in a printing-press, and a rotary cyl-

inder 2, which is understood to form a part of the press and to be suitably rotated to bring the paper against the form to cause the printing operation. The rotary cylinder 2 is provided with a plurality of gripping devices 50 A A A, embodying my present invention. These are shown mounted upon a long rod 3, which is understood to be suitably carried by the rotary cylinder 2 and operated in any well-known or desirable manner to cause it 55 to turn after the gripping devices pass the end of the feed-table 1, so as to cause them to close down on the paper, gripping the same to the rotary cylinder. Each gripping device A consists of a body or ring portion 4, 60 adapted to fit over the rod 3, and a finger 5, desirably made integral with the portion 4. The finger 5 consists of an inner portion a, which extends from its connection with the ring 4 outwardly and then curves backwardly 65 for substantially its entire length alongside the outside of the ring 4, and an outer portion b, which extends forwardly, preferably in a curve, from the rear end of the portion a. The ring portion 4 is provided with a set- 70 screw 6 to engage the rod 3, on which the gripping device is mounted. This construction provides a long bent gripping-finger, whose considerable length and bent shape causes it to be very elastic and springy. The 75 result is that the finger after striking the paper to grip it does not rebound therefrom, but maintains continuously its position and firm grip upon the paper.

It will be understood that changes can be 80 made in the construction of the device herein set forth without departing from the spirit of my invention. >

What I claim is—

1. A device of the class specified, comprising 85 a ring portion and a finger consisting of an inner portion connected to the ring portion and bent or doubled back alongside of the same for substantially the entire length of said inner portion, and an outer portion 90

extended forwardly from the end of the inner portion.

2. A device of the class specified, comprising a ring 4 provided with a set-screw 6, and 5 a finger 5 consisting of an inner portion *a* bent back alongside of the ring 4 for substantially the entire length of said portion *a*, and an outer portion *b*, extending in a curve out-

wardly and forwardly from the end of the inner portion *a*, substantially as described. 10

In witness whereof I hereunto subscribe my name this 26th day of December, A. D. 1902.

SEVERIN HALVORSON.
